DESIGN FOR AN EARRING OR SIMILAR ARTICLE

Abraham Brody, New York, N. Y.

Application July 27, 1945, Serial No. 121,017

Term of patent 3½ years

(Cl. D45—9)

To all whom it may concern:

Be it known that I, Abraham Brody, a citizen of the United States, residing at New York, in the county of New York and State of New York, have invented a new, original, and ornamental Design for Earrings or Similar Article, of which the following is a specification, reference being had to the accompanying drawing, forming a part thereof.

In the drawing:

Fig. 1 is a front elevational view of an earring or similar article, showing my new design; and

Fig. 2 is a side elevational view of the same drawn to a slightly larger scale.

I claim:

The ornamental design for an earring or similar article, as shown.

ABRAHAM BRODY.
